The ornamental design for an electrical cabinet, as shown and described.

DESCRIPTION

FIG. 1 is a first front perspective view of an electrical cabinet showing our new design;

FIG. 2 is a second front perspective view thereof;

FIG. 3 is a front elevation view thereof;

FIG. 4 is a front perspective view thereof, shown with the lid

in a closed position;

FIG. 5 is a rear perspective view thereof, shown with the lid

in a closed position;

FIG. 6 is an enlarged partial view of the area shown

encircled in FIG. 1; and,

FIG. 7 is an enlarged partial view of the area shown

encircled in FIG. 2.

The dashed broken lines in the drawings illustrate environmental subject matter that forms on part of the claimed design. The dash-dot broken lines in the drawings illustrate the boundaries of the encircled area and form no part of the claimed design.
